AUTOMATIC FLOW CONTROL SYSTEM FOR
ORE CONCENTRATORSEdmund C. Bitzer, Golden, Colo., assignor to
Colorado Iron Works Company, Denver, Colo.,
a corporation of Maine

Application September 18, 1948, Serial No. 49,928

1 Claim. (Cl. 209—155)

1

This invention relates to ore concentrators and dewaterers and more particularly to improvements in controlling flow through a concentrator such as shown in the application Serial No. 20,472, filed April 12, 1948, by Arthur J. Weinig.

In the application identified, the concentrates are delivered from the concentrator outlet pipe to a dewaterer by means of a pump and control valve. This pump and control valve provide the necessary differential pressure to effect flow through the concentrator. The pump, however, conveys all of the concentrate, which may be 50% solids, or more, and it is difficult to maintain the exact differential pressure required when pumping material which contains so much solid matter. Also, the valve must be throttled to adjust the rate of flow and it is apparent that it would be difficult to maintain an exact differential pressure when throttling flow of a mixture of water and solids. The rate of flow through the concentrator must, of course, bear an exact relationship to the rate of feed of pulp to the concentrator in order that the concentrator operate under optimum conditions. If, for example, the rate of discharge from the concentrator exceeds the rate of feed of pulp thereto, the pump will tend to withdraw all the pulp through the concentrator and there will thus be no gangue or tailings overflow from the concentrator and hence no concentration. On the other hand, if the rate of flow through the pump is less than required for optimum concentration, then there will be excessive overflow from the concentrator and much valuable ore will be carried along with the tailings. It is apparent, therefore, that with any predetermined rate of pulp flow to the concentrator, an exact differential pressure must be maintained between the concentrator overflow and the end of the concentrator discharge pipe in order that the concentrator operate most efficiently.

In any system which employs a pump to carry the concentrates the pump is subjected to considerable wear with its attendant change in pumping capacity because of the abrasive nature of the concentrates which pass therethrough. It would therefore be of further advantage to eliminate this pump, if possible.

The principal object of the present invention, therefore, is to provide an improved flow control for a concentrator.

Another object is to relate a concentrator and dewaterer in such manner that gravity head produces a flow through the concentrator which head is partially balanced by liquid in the dewaterer.

2

Another object is to produce optimum flow through a concentrator without employing a pump which conveys solids.

A further object is to relate the rate of discharge from a concentrator to the rate of feed of pulp thereto by an arrangement which is automatic in operation and effects an exact, unchanging differential pressure which produces optimum flow through the concentrator.

Another object is to provide an arrangement of a concentrator and dewaterer in which the rate of flow through the concentrator may be varied, as desired, without the use of a solids conveying pump or solids conveying valve.

Another object is to arrange the discharge of a concentrator with respect to a dewaterer in such manner that clogging of the concentrator discharge is eliminated.

Still further objects will become more apparent from a consideration of the description to follow, the appended claim, and the accompanying drawing, in which:

Figure 1 is a plan view showing the relative positions of the several elements;

Figure 2 is a section taken on line 2—2, Figures 1 and 2; and

Figure 3 is a side elevation taken on line 3—3, Figure 1, with parts thereof broken away and shown in section.

In the drawing reference character C designates a concentrator of the general type shown and described in the application above identified and D is a dewaterer or classifier of the screw type as shown at 11, with the conventional discharge 12 at its upper end over which flows de-watered solids. This dewaterer is representative of such devices of which there are many specifically different constructions available and which differ from the one shown principally in this, that rakes or conveyor belts are substituted for the screws.

Concentrator C has an overflow spout O near its top over which flows surplus water and gangue or tailings and an outlet pipe 10 at its bottom through which flows the concentrates for delivery to the dewaterer. The dewaterer is provided with an outlet 13 below level LC of the concentrator and a valve 16 is connected thereto which, by proper adjustment, will maintain any desired level in the dewaterer such as the level LD. It is to be particularly noted that valve 16 conveys water only, rather than solids; because separation of solids and the liquid delivered from the concentrator takes place in the dewaterer; the solids being de-watered and conveyed over upper edge 12 and the water being discharged through outlet

13. Since water may be effectively metered through a valve without clogging or changing in rate of flow for a given valve setting, it is apparent that once valve 16 is set for a given rate of feed to the concentrator level LD will remain unchanged. The head which produces flow through the concentrator is determined by the distance between LC and the bottom of the pipe 10, the specific gravity of the material in the concentrator and pipe 10, and the resistance which the pipe and concentrator offer to flow. This head is partially balanced by the head of the material in the dewaterer which is similarly determined, the distance between LD and the bottom of pipe 10 being one of the factors.

The relative levels of LC and LD will, of course, vary according to the nature of the ore being treated and the rate of flow desired through the concentrator. Lowering of level LD will increase the flow and raising the level will decrease the flow. No countercurrent flow should ever exist in pipe 10 which would carry fines upwardly to be ultimately lost in the gangue or tailing overflow O. Normally the level LD would be below LC by a distance h to produce the desired flow. It may of course be lowered by a distance h' which is determined by the position of outlet 13. Also, in some cases it may be desired to raise this level a distance h'' above level LC. For example, if the specific gravity of the material in the concentrator and its discharge pipe is considerably greater than the specific gravity of the material in the dewaterer then a theoretical static balance of the respective columns would occur when the two heads are in proportion to their specific gravities, that is level LD would be higher than LC. This would produce no flow, however, hence h'' would always be of such a value that some differential pressure would exist to produce flow.

A pump 14 is connected to overflow 13, but it is apparent that this pump does not control level LD in the embodiment previously disclosed. The pump merely delivers discharged fluid to any convenient point in the system, for example, through pipe 15 to a tank T for subsequent return to the concentrator through valve P. This return is illustrative only and it is apparent that the water from overflow 13 may be delivered to any place desired and that water supplied by valve P, when employed, may be received from any suitable source.

The control of level LD by means of a valve has been shown for illustration only, this being probably the simplest form in which the invention may be disclosed. It now becomes apparent that many other forms of level controls could be employed such as an adjustable weir or adjustable siphon having one leg thereof which would determine level LD. Also, an adjustable float could be employed which would maintain level LD as desired, as well understood in the art of level controls. Under certain circumstances it may also be desirable to control the level LD responsive to changes in the specific gravity of the material in the concentrator. Thus, if a portion of the pulp feed should change in specific gravity, the rate of flow through pipe would change if the level LD remained constant. Any suitable means known in the art, which would sense such change in specific gravity could be employed to regulate valve 15 so that flow conditions through pipe 10 would remain constant even with variable specific gravity of the pulp.

It is to be particularly noted, also, that the

5 concentrator and dewaterer are connected together by an inclined pipe 10. This inclined pipe forms the shortest possible straight connection between the two machines and thus prevents any clogging taking place therein as might occur with the use of a horizontal run of pipe, elbows, or other fittings which tend to obstruct flow.

10 While the invention has been disclosed with a dewaterer having a variable level, it is to be understood that other devices which provide a balancing fluid column could also be employed. Thus, the dewaterer might have a secondary function of classification of the ore concentrates hence the term "dewaterer" as used in the claim is to be given its broadest and most generic meaning within the spirit of the invention.

15 The present invention is to be distinguished from prior art arrangements wherein a concentrator delivers concentrates by gravity flow to a dewaterer. In these prior art devices there is no control of an optimum level of liquid in the dewaterer. Since the concentrates which are delivered to the dewaterer may be, for example, 50% solids and 50% water, and the dewatered material which is conveyed over the discharge 12 of the dewaterer may contain of the order of 80% solids, it becomes apparent that there is an excess of water being continuously delivered to the dewaterer which must be discharged somewhere in the system. The gangue overflow in the concentrator being the only place where this excess water may be discharged, there is thus established a countercurrent flow in the concentrator discharge conduit, that is at the same time that concentrates are being delivered to the concentrator there is a flow of water in the opposite direction through this conduit. This countercurrent flow of water carries with it certain of the fines which are carried over the gangue overflow of the concentrator and are thus either lost or necessitate further separation from the gangue if it is desired to recover them. The present invention, on the other hand, provides an exact control of flow conditions in the concentrator discharge conduit.

20 The provision of discharge 13 and control of level LC provide an arrangement which effects exact control of the flow conditions in discharge conduit 10. Thus, as previously mentioned, if it is desired to recover the fines along with the concentrates, which is usually the case, the flow conditions can be so regulated that no countercurrent flow exists in conduit 10 and all of the fines will be delivered to the dewaterer. It is, of course, apparent that the present invention could be employed, also, to achieve substantially the same results as described for the prior art. Thus, if it should not be desirable to recover the fines, or a portion thereof, the level LD could be regulated, if desired, to effect countercurrent in the concentrator discharge and discharge such fines over the gangue overflow.

25 Further, while the invention has been described with reference to a concentrator disclosed in the identified copending application, the principles of the invention may be employed with any type of concentrator wherein it is desired to regulate flow.

30 Having described the invention what is claimed as new is:

35 A concentrator and dewaterer unit for processing ore in series said units being arranged in laterally spaced relation, the concentrator having a gangue overflow at certain level and a concentrate discharge opening at a lower level, the gangue overflow and the concentrate discharge opening being in communication by a teeter col-

umn, the dewaterer unit having a normally open fluid outlet positioned at a level below the gangue overflow of the concentrator, a manually controlled valve forming means for adjusting the rate at which fluid flows through said fluid outlet, manually adjustable means for feeding ore pulp to the concentrator at a predetermined rate, and means for adjusting the rate of flow of material through the concentrator by varying the effective hydrostatic head producing such flow said means comprising the valve in the fluid outlet from the dewaterer.
